Primary Examiner — Manpreet S Matharu*Assistant Examiner* — Suzanne E Tisdell(74) *Attorney, Agent, or Firm* — Westbridge IP LLC(57) **CLAIM**

The ornamental design for a portable emergency storage tank, as shown and described.

DESCRIPTION

FIG. 1 is a top, front and left side perspective view of a portable emergency storage tank showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear and right side perspective view thereof.

The broken lines in the drawings illustrate the portions of the portable emergency storage tank which form no part of the claimed design.

1 Claim, 8 Drawing Sheets
